UNITED STATES PATENT OFFICE.

LIONEL M. WOOLSON, OF DETROIT, MICHIGAN, ASSIGNOR TO PACKARD MOTOR CAR COMPANY, OF DETROIT, MICHIGAN, A CORPORATION OF MICHIGAN.

HYDROCARBON MOTOR.

Application filed December 9, 1920. Serial No. 429,588.

This invention relates to hydrocarbon motors, and particularly to mixture forming and supplying means therefor.

The invention is particularly adapted to a motor having a combustion device or fuelizer which has a suction line, and one of the objects of the invention is to control the carburetor mixture by the suction of said combustion device.

Other objects of the invention will appear from the following description taken in connection with the drawings, which form a part of this specification, and in which:

Fig. 1 is a side elevation of a fragment of a hydrocarbon motor embodying this invention, parts being broken away to show interior construction;

Fig. 2 is a somewhat enlarged horizontal section substantially on the line 2—2 of Fig. 1;

Fig. 3 is a vertical section on the line 3—3 of Fig. 2; and

Fig. 4 is a fragmentary view of a portion of Fig. 3, showing the valve in closed position.

Referring to the drawings, 10 is a portion of cylinder casting of a hydrocarbon motor and 11 is the intake pipe leading thereto. The intake pipe is shown as divided into two passages 12 and 13 and at its lower end a carburetor 14 is connected to it. The carburetor comprises the usual float chamber 15, main air intake 16, auxiliary air intake 17 and a throttle valve 18 of butterfly form.

The throttle valve may be operated manually as by an arm 19 and a control rod 20.

Connected to a suitable part of the intake manifold 11, preferably above the throttle 18, is a combustion device or heater; sometimes called a "fuelizer". It comprises a combustion chamber 21 in the form of a jacket around part of the intake header with a screened inlet opening at 22, one or more outlets 23, into the intake pipe above the throttle valve, and a spark plug 24, for firing the mixture in the chamber. The suction line of the combustion device extends from its inlet 22, in the form of piping 25 and 26 to one end of the shaft of the

throttle valve 18. The throttle valve shaft is shown in Fig. 2 and is indicated at 27. It is drilled longitudinally as at 28 and a port 29 extends downwardly when the throttle valve is in its closed position

as shown in Fig. 1. The outer end of the passage 28 communicates with the interior of the pipe 26 so that when the throttle is closed, since the outlets 23 of the combustion device are above the throttle valve, mixture may be drawn through the port 29, passage 28, pipes 25 and 26 and inlet 22 to the combustion chamber where it will be fired by the spark plug 24. The burnt products of combustion will pass into the intake pipe 11 and heat the mixture as it is drawn into the motor.

It is sometimes desired to weaken the mixture of the carburetor for certain running conditions without affecting the idling of the motor or the full throttle opening condition of the motor. The present invention contemplates the use of the suction line of the combustion device for controlling the mixture of the carburetor in this respect. The carburetor shown has a float chamber 15 of the usual type in which a float 30 maintains the liquid fuel at the desired level. The adjustable valves or other parts of the carburetor are set in the usual manner for obtaining the best result for idling and throughout its range of action. The float chamber 15 is provided with a cover 31 in which there is an opening 32. A casting 33 is screwed into the opening 32 and a port 34 extends through the casting. The outer end of this port 34 communicates with the atmosphere through a cross passage 35 and a pipe 36, which latter extends to a drain pipe 37, which also connects with the lower part of the main intake 16 of the carburetor so that any gasoline overflow or condensation that may accumulate in these pipes will be drained to the ground where it will cause no harm.

The port 34 is controlled by a valve 38 which is sufficiently heavy to close the port 34 by its weight. It slides in a bore 39 aligned with the port 34. In Fig. 3 the valve is shown slightly raised from its seat and in Fig. 4 it is in closed position. It will be seen that with the valve in its raised position the upper part of the float chamber communicates with the air at atmospheric pressure through the port 34, passage 35 and pipes 36 and 37. Thus it is free to feed gasoline or other liquid fuel to the fuel nozzle 16 of the carburetor without restriction.

However, by closing the valve 38 and creating a suction or partial vacuum in the

upper part of the float chamber, the feed of fuel from the float chamber will of course be somewhat retarded and the carburetor mixture will be thereby weakened. To produce this suction or partial vacuum, the upper part of the float chamber is connected with the suction line of the combustion device as by a restricted passage 40. This passage 40 is preferably very small so that the air passing through it to the combustion device will not materially weaken the mixture of that device.

Now with the valve 38 closed, as in Fig. 4, whatever depression there is in the suction line 25, 26 of the combustion device will be communicated to the float chamber and the flow of fuel therefrom will be correspondingly retarded. When the valve 38 is raised from its seat as in Fig. 3 the suction line of the combustion device will have no effect upon the float chamber because of the large atmosphere port 34 which will then be open.

In order that the valve 38 may be raised from its seat when the throttle valve 18 is in substantially closed position, as for idling the motor, a connecting link 41 and a bell crank lever 42 are provided. The horizontal arm 43 of the bell crank lever projects into the slot 44 formed in the head of the valve 38 and as the lever is rocked the valve 38 is lifted from its seat. A pin-and-slot connection 45 between the rod 41 and the bell crank lever 42 permits of lost motion of the rod 41 during the greater part of the movement of the throttle valve 18. It is only the final closing moving of the valve 18 which operates to raise the valve 38 from its seat.

It has been found that in some cases the suction created by the above described means is too great for obtaining the best results and means therefore have been provided for limiting the possible depression in the float chamber. This means is in the form of a submerged vent which admits air to the float chamber only after the liquid has been depressed a certain amount in a chamber arranged parallel with the float chamber. As shown this parallel chamber is formed by a tube 46 which in this instance is secured to the valve 38 and is raised and lowered with it. The tube 46 extends through the port 34 and is opened at its lower end below the normal level of the liquid in the float chamber. At its upper end it has openings 47 which communicate with the passage 35 and pipe 36 and consequently with the air at atmospheric pressure. A very restricted opening or port 48 is formed in the pipe 46 above the level of the liquid in the float chamber. This port is somewhat smaller than the port 40 and to some extent modifies the operation of the submerged vent.

It will be seen that with the valve 38 in closed position, the suction at the port 40 can reduce the pressure in the float chamber only to the point where the liquid in the tube or chamber 46 is depressed to the bottom thereof. Thereafter air will be drawn through the tube 46 to maintain the pressure in the float chamber at that point.

From the above it will be seen that by reason of the interconnection between the throttle valve 18 and the valve 38, the latter is raised from its seat when the throttle is closed for idling and the carburetor will operate to give the desired rich mixture, but when the throttle valve 18 is partly opened the valve 38 is seated and the suction of the combustion device will create a partial vacuum in the float chamber which will retard the flow of liquid fuel therefrom and thereby weaken the mixture supplied by the carburetor. Again, when the throttle valve is opened wide, the combustion device will become practically inoperative because the pressure on both sides of the throttle valve is substantially equal, and there will then be no suction on the float chamber and consequently the latter will supply the normal amount of fuel to the carburetor thus permitting the motor to develop its greatest power. Under this latter condition the port 48 will form a vent for the float chamber through the pipe 46, passage 35 and pipe 36.

It will be understood that other forms and modifications may be made without departing from the spirit or scope of this invention.

Having thus described my invention, what I claim and desire to secure by Letters Patent is:—

1. In a hydrocarbon motor, the combination with a carburetor having a float chamber, of a combustion heater having a suction line, means connecting said float chamber with said suction line, and valve controlled means for admitting air at atmospheric pressure to said float chamber.

2. In a hydrocarbon motor, the combination with a carburetor having a float chamber, of a combustion heater having a suction line, means comprising a restricted passage connecting said float chamber with said suction line, and valve controlled means for admitting air at atmospheric pressure to said float chamber.

3. In a hydrocarbon motor, the combination with a carburetor having a float chamber, of a combustion heater having a suction line, means connecting said float chamber with said suction line, and means for limiting the possible depression in the float chamber.

4. In a hydrocarbon motor, the combination with a carburetor having a float chamber, of a combustion heater having a suction line, means connecting said float chamber with said suction line, and means comprising

ing a chamber open to the lower part of the float chamber, for limiting the possible depression in the float chamber.

5. In a hydrocarbon motor, the combination with a carburetor having a float chamber, of a combustion heater having a suction line, means connecting said float chamber with said suction line, and means for controlling the depression in said float chamber comprising a chamber open to the interior of the float chamber below the liquid level therein and open to the atmosphere above.

6. In a hydrocarbon motor, the combination with a carburetor having a float chamber, of a combustion heater having a suction line, means connecting said float chamber with said suction line, means for controlling the depression in said float chamber comprising a chamber open to the interior of the float chamber below the liquid level therein and open to the atmosphere above, and a valve controlled atmosphere vent means for said float chamber.

7. In a hydrocarbon motor, the combination with a carburetor having a float chamber and a throttle valve, of a combustion heater having an inlet below said throttle valve and an outlet above said throttle valve, means connecting the float chamber above the liquid level with the suction line of said combustion heater, and valve controlled means for admitting air at atmospheric pressure to said float chamber.

8. In a hydrocarbon motor, the combination with a carburetor having a float chamber and a throttle valve, of a combustion heater having an inlet below said throttle valve and an outlet above said throttle valve, means connecting the float chamber above the liquid level with the suction line of said combustion heater, means for limiting the possible depression in said float chamber, and valve controlled means for admitting air at atmospheric pressure to said float chamber.

9. In a hydrocarbon motor, the combination with a carburetor having a float chamber and a throttle valve, and means for operating the throttle valve, of a combustion device having a suction line connected below the throttle valve, means connecting the float chamber with said suction line, valve controlled means for admitting air at atmospheric pressure to said float chamber,

and means operated by the movement of said throttle valve for opening the valve of said valve controlled means as the throttle valve is closed.

10. In a hydrocarbon motor, the combination with a carburetor having a float chamber, and a combustion device having a suction line, of means comprising a restricted passage connecting said suction line with the upper part of said float chamber, a tube extending into said float chamber below the level of the liquid therein and being open at its lower end, said tube being open to the atmosphere at its upper end, said float chamber having a port above the liquid level communicating with the atmosphere, and a valve for closing said port.

11. In a hydrocarbon motor, the combination of a carburetor having a float chamber, said float chamber having a port from its upper part to the atmosphere, a tube extending through said port and into the float chamber below the liquid level therein, said tube being open at its lower end and having communication with the atmosphere at its upper end, a valve for closing said port, said valve being connected to said tube, and means for operating said valve.

12. In a hydrocarbon motor, the combination of a carburetor comprising a float chamber having a cover, said cover having a port therethrough, a sliding valve adapted to control said port, means for operating said valve, and a tube connected to said valve and extending through said port into the float chamber.

13. In a hydrocarbon motor, the combination with a carburetor having a float chamber, a combustion device having a suction line, and means connecting said float chamber with said suction line, of an automatically controlled submerged vent for said float chamber for controlling the repressure therein.

14. In a hydrocarbon motor, the combination with a carburetor having a float chamber, a combustion device having a suction line, and means connecting said float chamber with said suction line, of a submerged vent for said float chamber, and valve controlled means for admitting air at atmospheric pressure to said float chamber.

In testimony whereof I affix my signature.

LIONEL M. WOOLSON.
